United States Patent Office

Des. 229,347
Patented Nov. 20, 1973

229,347

RADIO RECEIVER OR SIMILAR ARTICLE

Daisuke Kajiwara, Fukuoka, Japan, assignor to Matsushita
Electric Industrial Co., Ltd., Osaka, Japan

Filed Oct. 12, 1971, Ser. No. 188,653

Claims priority, application Japan Apr. 15, 1971

Term of patent 14 years

Int. Cl. D14—03

U.S. Cl. D56—4 B

FIG. 1

FIG. 2

FIG. 3

FIG. 4

FIG. 5

FIG. 6

FIG. 1 is a front perspective view of a radio receiver or similar article, showing my new design in opened position with one section rotated 90 degrees with respect to the other section;

FIG. 2 is a rear perspective view in opened position with one section rotated 90 degrees with respect to the other section;

FIG. 3 is a side elevational view in opened position with one section rotated 90 degrees with respect to the other section;

FIG. 4 is a top perspective view in closed position;

FIG. 5 is a bottom perspective view in closed position; and

FIG. 6 is a perspective view thereof in opened position with one section rotated 180 degrees with respect to the other section.

I claim:

The ornamental design for a radio receiver or similar article, as shown and described.
